UNITED STATES PATENT OFFICE.

STACY B. HASELTINE, OF CHICAGO, ILLINOIS, ASSIGNOR, BY MESNE ASSIGNMENTS, TO
W. H. MINER, INC., A CORPORATION OF DELAWARE.

FRICITION SHOCK-ABSORBING MECHANISM.

Application filed January 21, 1924. Serial No. 687,529.

This invention relates to improvements in friction shock absorbing mechanisms.

One object of the invention is to provide a friction shock absorbing mechanism, especially adapted for railway draft riggings, wherein is obtained high capacity and certain release.

A more specific object of the invention is to provide a friction shock absorbing mechanism wherein are employed a plurality of differential wedge elements, and an auxiliary yoke having wedging means thereon coacting with the differential wedges.

Other objects and advantages of the invention will more clearly appear from the description and claims hereinafter following.

In the drawings forming a part of this specification, Figure 1 is a horizontal, longitudinal, sectional view of a portion of a railway draft rigging, showing my improvements in connection therewith. Figure 2 is a vertical, longitudinal sectional view corresponding substantially to the line 2—2 of Figure 1. Figure 3 is a detailed, perspective view of one of the spring followers. And Figure 4 is a view similar to Figure 1, illustrating a different embodiment of the invention.

In said drawings, referring first to the construction illustrated in Figures 1, 2 and 3, 10—10 denote channel shaped center or draft sills of a railway car underframe, to the inner faces of which are secured front stop lugs 11 and rear stop lugs 12 arranged in the usual manner. A portion of the drawbar is indicated at 13, to which is secured a yoke 14 of well known form. The shock absorbing mechanism proper, hereinafter described, is disposed within the yoke. All the movable parts of the draft rigging are arranged to be supported by a detachable saddle plate 16.

The improved shock absorbing mechanism proper, as shown in Figures 1, 2 and 3, comprises broadly, a pair of front and rear followers A—A; a spring cage B; four end wedges C—C; an auxiliary yoke D; front and rear sets of twin spring resistance elements E—E; and front and rear spring followers F—F.

The front and rear followers are of like construction, each being of hollow, rectangular form and having interior opposed side wedge faces 17—17 diverging inwardly or

toward the center of the mechanism. Each follower is also provided with a transverse, flat outer face 18 adapted to coact with the corresponding stop lugs in the usual manner.

The spring cage B is in the form of a hollow, rectangular casing open at the front and rear ends. The casing is divided into front and rear chambers by a vertically disposed, transverse, central partition wall 118 formed integral therewith.

The four wedges C—C, which are of like construction, are arranged in pairs at opposite ends of the mechanism, one pair coacting with the front follower and the other with the rear follower. Each wedge C is in the form of a block having a transverse, inner flat face 19 engaging the corresponding spring follower F, and a pair of outwardly converging wedge faces 117 and 20, the wedge face 117 of each block C being correspondingly inclined to and adapted to coact with the adjacent wedge face 17 of one of the followers A. At the inner end, each of the blocks C is also formed with a centrally disposed, cylindrical guide and retaining lug 21 working in one of a pair of guide slots 22—22 provided in the corresponding spring follower F. The lugs coact with the slots to limit the relative separation of the wedge blocks of each pair thereby retaining the blocks in assembled relation with the yoke and other parts before being applied to the car, and also preventing excessive separation of the blocks after the mechanism has been applied to the car.

The auxiliary yoke D is in the form of a relatively heavy casting having a central opening 23 defined by upper and lower longitudinally disposed arms 24—24, and vertically disposed end sections 25—25. Each end section 25 is cut away at the opposite sides as clearly shown in Figure 1, to provide a pair of inwardly converging wedge faces 120—120, each adapted to coact with the wedge face 20 of one of the wedge blocks C. At each end, the yoke D is provided with a vertically disposed flat transverse face 26 adapted to abut the inner surface of the end wall of the corresponding follower when the mechanism is fully compressed. The parts are preferably so proportioned that there will be a slight clearance as indicated at 27 between each spring follower and the corresponding inner end wall of the

yoke, when the parts are in normal position, so that the expansive action of the springs E will maintain the wedge blocks engaged with the wedge faces of the yoke, and the 5 lugs 21 at the outer ends of the slots 22.

As clearly shown in the drawings, the spring cage B is disposed within the opening 23 of the yoke, having limited movement therein, a slight clearance being provided 10 between the opposite ends of the cage B and the yoke. In this connection, it is pointed out that the opposite ends of the yoke and the opposite ends of the spring cage are normally spaced from the inner faces of the end 15 walls and the inner ends of the front and rear followers respectively, as shown, the total spacing between the cage and the two followers A being equal to the permissible stroke of the mechanism. Both the yoke D 20 and the spring cage B are freely movable between the front and rear followers of the mechanism.

The spring resistance elements E are four in number, two being disposed in twin arrangement in each chamber of the spring cage B, and the two sets of twin spring resistance elements being arranged at the front and rear ends of the mechanism. Each 25 spring resistance element E comprises a relatively light inner coil and a relatively heavier outer coil bearing at their inner ends on the central partition 118. The springs are preferably placed under initial compression when the parts are assembled to maintain the 30 wedge blocks engaged with the wedge faces of the yoke and the guide and retaining lugs at the outer ends of the corresponding slots. 35

The spring followers F are two in number, one being disposed at each end of the mechanism between the corresponding wedge blocks C and the outer ends of the adjacent pair of twin springs. Each spring follower 40 is in the form of a rectangular plate, having a flat outer surface 28 adapted to slidably receive the flat end faces 19 of the corresponding pair of wedge blocks C.

The operation of the mechanism shown in Figures 1, 2 and 3, is as follows. Upon relative approach of the front and rear followers A—A in either buff or draft, a wedging 45 action will be set up between the coacting wedge faces of the followers and the respective blocks C, the blocks C being forced inwardly against the resistance of the springs E, longitudinally toward the center and laterally toward the axis of the mechanism, the wedge faces 20 of the blocks slipping on the corresponding wedge faces 120 of the yoke D. The floating yoke D moves in a direction 50 in line with the applied force, either buff or draft at a rate equal to one-half the speed of the follower to which the force is applied, the opposite ends of the same acting in the manner of wedges relatively fixed with reference to each other. During the compres-

sion stroke of the mechanism, as the blocks C slide laterally on the faces 28 of the respective spring followers, friction, in addition to that created between the various wedge faces, will also be created between the 50 end faces 19 of the blocks and each spring follower. The compression of the mechanism continues until the inner surfaces of the end walls of the front and rear followers are brought into abutment with the opposite 75 ends of the yoke D and the inner ends of the respective followers engage the opposite ends of the spring cage B, whereupon the forces will be transmitted directly through the yoke D and cage B, which together function 80 as a column-load-sustaining means transmitting the forces to the center sills. Upon removal of the actuating pressure, expansion of the spring elements E effects return of all the parts to normal position. 85

Referring next to the construction illustrated in Figure 4, the improved shock absorbing mechanism comprises, broadly, front and rear follower casings A'—A'; four end wedges C'—C'; an auxiliary yoke D'; twin 90 spring resistance elements E'—E'; and front and rear spring followers F'—F'.

The front and rear follower casings A'—A' are of like construction, each being of rectangular outline, and having spaced 95 top, bottom, end and side walls, and being open at their inner ends. At the outer closed end of each casing A', a pair of interior opposed side wedge faces 130—130 are provided, diverging inwardly or toward the 100 center of the mechanism. The inner ends of the casings A' are normally spaced apart a distance equal to the permissible stroke of the mechanism, so that when the same is compressed, the inner ends of the casings will 105 abut, acting in the manner of column-load-sustaining members.

The four wedges C'—C' are in all respects similar to the wedges C—C hereinbefore described, each being provided with a flat inner end face 119 and a pair of outwardly converging wedge faces 131 and 120, adapted to coact respectively with the corresponding wedge face 130 of one of the followers A' and one of the wedge faces 132 at the corresponding end of the yoke D'. 110

The yoke D' is in all respects similar to the yoke D hereinbefore described, the same having a central opening 123 defined by upper and lower arms 124 and end sections 125. 120 The yoke is also provided with flat front and rear faces 126 adapted to coact with the inner surfaces of the front and rear followers A' respectively.

The spring followers F', which are disposed in the central opening 123 of the yoke D', are similar to the followers F, each being in the form of a rectangular plate having a pair of slots 122—122 therein, each adapted to slidably receive a guide and 125 reference to each other. During the compres-

taining lug 121 inwardly projecting from the corresponding wedge block C'. The parts are so proportioned that there will normally be a slight clearance between each 5 spring follower and the corresponding inner end wall of the yoke, for a purpose similar to that hereinbefore described in connection with the embodiment of the invention illustrated in Figures 1, 2 and 3.

10 The spring resistance elements E' are two in number, being disposed in twin arrangement between the front and rear spring followers F' and each comprising an inner relatively light coil and an outer relatively 15 heavier coil. The springs are preferably placed under initial compression when the parts are assembled, thereby maintaining the wedge blocks engaged with the yoke and the guide and retaining lugs at the outer 20 ends of the corresponding slots, limiting the separation of the wedges and maintaining the same assembled with the yoke and other parts.

25 The operation of the mechanism illustrated in Figure 4 is the same as that hereinbefore described in connection with the construction illustrated in Figures 1, 2 and 3.

30 From the preceding description, taken in connection with the drawings, it will be evident that in both embodiments of the invention illustrated, I have provided exceptionally great column strength, in that in each instance, when the mechanism is fully compressed, the entire force is transmitted along 35 the four sides and the center line of the mechanism.

I have herein shown and described what I now consider the preferred manner of carrying out my invention but the same is merely 40 illustrative and I contemplate all changes and modifications that come within the scope of the claims appended hereto.

I claim:

45 1. In a friction shock absorbing mechanism, including a drawbar and a yoke, the combination with an auxiliary yoke mounted within and extending longitudinally of said first named yoke; of movement resisting mechanism coacting with and supported by 50 said first named yoke and supporting said auxiliary yoke independently thereof, said movement resisting mechanism including wedge members coacting with the opposite ends of said auxiliary yoke.

55 2. In a friction shock absorbing mechanism, the combination with relatively movable front and rear followers having wedge means thereon; of a yoke interposed between said followers, said yoke having wedge means at the opposite ends thereof; wedge blocks coacting with each of said followers and said yoke; and a spring resistance coacting with said wedge blocks.

60 3. In a friction shock absorbing mechanism, the combination with relatively mov-

able end followers; a yoke element; a spring resistance within said yoke; wedge members at opposite ends of said spring resistance; and wedge means on said yoke and followers coacting with said wedge members to move 70 the latter laterally while forcing the same toward each other longitudinally of the mechanism.

4. In a friction shock absorbing mechanism, the combination with relatively movable end followers, each having wedge means associated therewith; of a longitudinally disposed column element having wedge means at the opposite ends thereof said element being interposed between said followers and adapted to be engaged by the latter on full compression of the mechanism; a wedge member coacting with the wedge means of each follower and the wedge means of the corresponding end of the 80 column element; and yielding means for opposing movement of said wedge members.

5. In a friction shock absorbing mechanism, the combination with relatively movable end followers each having wedge means 90 thereon; of a column element interposed between said followers, said column element having the opposite ends thereof in engagement with the followers when the mechanism is fully compressed to limit relative 95 movement of said followers, said element having wedge means at the opposite ends thereof; a spring cage interposed between said followers, said cage having abutment means thereon; a pair of wedges co-acting 100 with said wedge means of each follower and the corresponding end of said element; and yielding means interposed between said wedges and said abutment means of said cage.

105 6. In a friction shock absorbing mechanism, the combination with relatively movable end followers; of a yoke interposed between said followers; a spring resistance; wedge means coacting with the respective 110 followers and the adjacent end of the yoke; a pair of spring followers disposed within said yoke, one of said spring followers being interposed between the wedge means coacting with each of said end followers 115 and the adjacent end of said spring resistance.

7. In a friction shock absorbing mechanism, the combination with relatively movable end followers; of a yoke interposed between said followers and adapted to be engaged by said followers to limit the relative approach of the same; a spring resistance; and wedge means coacting with said followers and yoke.

120 8. In a friction shock absorbing mechanism, the combination with relatively movable end followers; of a yoke interposed between said followers; a spring cage within said yoke; spring resistance elements with- 130

in said cage; and wedging means respectively coacting with said yoke and followers.

9. In a friction shock absorbing mechanism, the combination with relatively movable end followers; of a longitudinally disposed yoke between said followers, said yoke being of a length to limit the relative approach of said followers; a spring cage disposed within said yoke, said spring cage being adapted to engage said followers to limit their relative approach; a spring resistance element within said cage; and wedge means coacting with said yoke and followers.

10. In a friction shock absorbing mechanism, the combination with relatively movable end followers; a set of end wedges coacting with each follower; a yoke disposed between said followers and coacting with each set of end wedges; a double-ended spring cage within said yoke; and front and rear springs within said cage coacting with said wedges.

11. In a friction shock absorbing mechanism, the combination with relatively movable followers; of wedge means coacting with said followers; column-load-sustaining means coacting with said followers, said last named means including a shell and a yoke

interposed between said followers, said yoke having wedge faces thereon coacting with 30 said wedge means; and means yieldingly resisting movement of said wedge means.

12. In a friction shock absorbing mechanism, the combination with relatively movable end followers; of a yoke interposed between said followers; a spring resistance; wedge means coacting with each follower and the adjacent end of the yoke; a pair of spring followers; and interengaging means on said spring followers and wedges for limiting relative separation of the wedges associated with each follower.

13. In a friction shock absorbing mechanism, the combination with relatively movable end followers; of a yoke element; a 45 spring resistance within said yoke; spring followers; wedge members; and wedge means on said yoke and end followers coacting with said wedge members to slide the same laterally on said spring followers while 50 forcing the former toward each other longitudinally of the mechanism.

In witness that I claim the foregoing I have hereunto subscribed my name this 18th day of January, 1924.

STACY B. HASELTINE.
